VENTILATING APPARATUS

Francis C. Kilb, Larchmont, N. Y., assignor to
American Radiator Company, New York, N. Y.,
a corporation of New Jersey

Application April 9, 1936, Serial No. 73,461

5 Claims. (Cl. 98—41)

My invention relates to ventilating apparatus and more particularly to mechanism for operating a damper for controlling the flow of air through such an apparatus.

5 Objects of my invention are comprised in the provision of an improved form of damper operating mechanism for ventilating apparatus which is simple in construction, which is inexpensive to manufacture, which provides for holding the 10 damper at any selected one of a number of positions, and one which, in its preferred embodiment, projects a minimum distance beyond the enclosing casing of the ventilating apparatus.

15 The invention consists in the novel construction and combination of parts, to be more fully described hereinafter, and the novelty of which will be particularly pointed out and distinctly claimed.

20 In the accompanying drawing, to be taken as a part of this specification, I have fully and clearly illustrated a preferred embodiment of my invention, in which drawing—

25 Fig. 1 is a transverse vertical sectional view showing the application of my invention to one form of ventilating apparatus;

Fig. 2 is an enlarged fragmentary horizontal sectional view taken on the line 2—2 of Fig. 1;

Fig. 3 is a front elevation of the damper operating mechanism shown in Fig. 2; and

30 Fig. 4 is a detail vertical section taken on the line 4—4 of Fig. 3.

Referring now in detail to the construction illustrated, the reference numeral 10 indicates a casing for a ventilating apparatus arranged partially 35 in front of and partially beneath a hollow window sill 11 for a wall of a room. The hollow window sill 11 provides a passage 12 connecting the interior of the casing, through an opening 13, with the outside atmosphere. A damper 14 is 40 pivotally mounted as indicated at 15 within the opening 13 and serves to control the flow of fresh air into an inlet chamber 16 of the casing 10.

A motor-driven blower unit 17 is mounted within 45 the casing 10 and operates to force the fresh air from the inlet chamber 16 through an outlet chamber 18 and through outlet openings 19 in the upper portion of the casing and into the room. A filter 20 is suitably arranged behind the blower unit 17 and serves to eliminate dust particles from 50 the entering fresh air. A suitable heating unit 21 is disposed in the lower part of the outlet chamber 18 of the casing 10. Room air enters the casing through an opening (not shown) in the lower portion of the casing, and is heated as it passes 55 over the surfaces of the heating unit 21 and the

heated air flows upwardly into the room through the outlet openings 19, previously mentioned.

The damper 14 is connected by means of an extensible link means 25 with a damper-operating mechanism indicated generally by the reference character 26, and secured to the outside front wall of the casing.

The damper-operating mechanism 26 is constructed preferably as a unit and comprises a lever 27 fulcrumed by a pin 28 carried by the outer end 10 of spaced brackets 29, the latter being fixed to and extending interiorly from a supporting plate 30. One end of the lever 27 is pivotally connected to the end of the link 25 remote from the damper 14. The lever includes an operating element 31 15 which extends exteriorly of the casing through a suitable slot formed in the supporting plate 30. The supporting plate 30 is secured to the front of the casing within an opening 32 in the exterior wall structure thereof by means of a clamping 20 plate 33 and screws 34, the peripheral edges of the supporting plate 30 and clamping plate 33 engaging the peripheral edges of the wall structure defining the opening 32.

As stated, the lever 27 is fulcrumed by a pin 28 25 carried by the inner ends of spaced brackets 29. The lever 27 is arranged between the brackets 29 and is provided with a longitudinally extending slot 35 which receives the fulcrum pin 28. The fulcrum pin and slot connection provide for arcuate movement of the lever about the pin 28 and provide for longitudinal movement of the lever a distance limited by the length of the slots 35.

The operating element 31 may be considered as a part of the lever or as a separate element. The 35 element 31 is in the form of a flat sector-shaped plate 36 which is fixed at one end to an end of the lever 27 and is formed with oppositely arranged arcuate edge surfaces 38 and 39 which are substantially concentric with arcs described 40 by points on the lever 27 when moved about its fulcrum pin 28. The arcuate surface 38 is provided with a series of notches 40 and the supporting plate 30 is provided with a tongue element 41 45 fixed thereto and adapted to engage any selected one of the notches 40.

In order to assure engagement of the tongue 41 with the selected one of the notches 40 and thereby hold the lever 27 and damper 14 at a desired position, the lever is provided with a 50 pair of spaced inwardly-extending brackets 43 which are connected at their outer ends to the ends of springs 44, and the latter are connected at their other ends to an inwardly-extending bracket 45 formed integral with the tongue ele- 55

ment 41 and fixed to the supporting plate 30. The springs 44 serve to urge the lever 27 longitudinally to effect engagement of the tongue element 41 with a selected one of the notches 40.

5 From the above description, it will be readily seen that in order to move the damper, the operating element 31 is simply grasped by the hand and the lever easily moved lengthwise of its slot 35 so that the defining wall surfaces of the notches 40 will clear the tongue element 41. In this position, the lever 27 can be easily moved about its fulcrum pin 28 to adjust the position of the damper to any point desired. The lever may then be released and the springs will quickly effect the 10 engagement of the tongue with the adjacent notch.

15 The operating element 31 is preferably in the form of an arcuate-shaped sector so that it will protrude into the room a minimum distance when it is at its extreme outer position, which is the position shown in full lines. The lever 27 with its pin and slot connection with the brackets 29 provides for easily moving the damper 14 in either direction and for movement of the lever 25 lengthwise to effect engagement and disengagement of the tongue member and notches so that the damper may be held at any desired position. The springs 44 also provide against accidental disengagement of the tongue and notches.

20 30 What I claim and desire to secure by Letters Patent of the United States is:—

1. Operating mechanism for a damper comprising, in combination, a support member; a lever member adapted to be operatively connected to the damper; fulcrum means connecting said lever member and said support member and providing for arcuate movement of said lever member about an axis and for limited movement of said lever member in a lengthwise direction; said lever 35 member including an operating element adapted to be grasped by hand to effect arcuate movement of said lever member about its fulcrum axis and to effect said limited lengthwise movement of said lever member; one of said members having a plurality of notches formed therein and being arranged in an arc substantially concentric with those described by points on said lever member when moved about its fulcrum axis; the other of said members having a tongue element fixed 40 thereto and arranged to fit within any selected one of said notches when said lever member is at one extremity of said lengthwise movement and to clear the surfaces defining said notches when said lever member is at the other extremity 45 of said lengthwise movement; and means for constantly urging said lever member lengthwise in a direction to effect engagement of said tongue element with said notches.

50 2. Operating mechanism for a damper comprising, in combination, a support; a lever adapted to be operatively connected to the damper; fulcrum means connecting the lever and support and providing for arcuate movement of said lever about an axis and for limited movement of said 55 lever in a lengthwise direction; said lever including an operating member adapted to be grasped by hand to effect the arcuate movement of said lever about its fulcrum axis and to effect the limited lengthwise movement of the lever; said lever having a plurality of notches formed 60 therein and being arranged in an arc substantially concentric with those described by points on said lever when moved about its fulcrum axis; a tongue member fixed to said support and arranged to fit within any selected one of the notches when the lever is at one extremity of its lengthwise movement and adapted to clear the surfaces defining the notches when the lever is at the other extremity of its lengthwise movement; and means for constantly urging said lever lengthwise in a direction to effect engagement of the tongue and the notches so as to hold the lever and damper at any desired position.

65 notches when the lever is at one extremity of its lengthwise movement and adapted to clear the surfaces defining the notches when the lever is at the other extremity of its lengthwise movement; and spring means connecting said lever and said support and constructed to urge the lever lengthwise in a direction to effect engagement of the tongue and the notches so as to hold the lever and damper at any desired position.

70 3. Operating mechanism for a damper comprising, in combination, a support; a fulcrum pin carried by said support; a lever adapted to be operatively connected to the damper and having a slot therein extending lengthwise thereof and receiving said pin; said lever including an operating member having a portion adapted to be grasped by hand to effect movement of said lever about its fulcrum and to effect movement of said lever lengthwise an amount determined by the length of the slot; said lever having a plurality of notches formed therein and being arranged in an arc substantially concentric with those described by points on said lever when moved about its fulcrum axis; a tongue fixed to said support and arranged to fit any selected one of the notches when the fulcrum pin is at one end of the slot and to clear the surfaces defining the notches when the fulcrum pin is at the other end of the slot; and a spring connecting the lever and support and constantly urging the lever lengthwise in a direction to effect the engagement of the tongue and the notches so as to hold the lever and damper at a desired position.

75 4. Operating mechanism for a damper comprising, in combination, a support; a lever adapted to be operatively connected to the damper; fulcrum means connecting the lever and support and providing for arcuate movement of said lever about an axis and for limited movement of said lever in a lengthwise direction; an operating member fixed to one end of the lever and movable therewith and including a curved edge portion facing away from the fulcrum and lying in an arc substantially concentric with those described by points on said lever when moved about its fulcrum axis; said operating member having a plurality of notches formed in said edge portion opening away from the fulcrum; a tongue member fixed to said support and arranged to fit within any selected one of the notches when the lever is at one extremity of its lengthwise movement and adapted to clear the projecting surfaces defining the notches when the lever is at the other extremity of its lengthwise movement; and spring means connecting said lever and said support and constructed to urge the lever lengthwise in a direction to effect engagement of the tongue and the notches so as to hold the lever and damper at any desired position.

80 5. In ventilating apparatus, walls defining an enclosing casing structure; a damper for controlling the flow of air through said casing structure; a supporting member arranged within the plane of and carried by one of said defining walls and having an opening therein connecting the interior and exterior of the casing; a lever arranged interiorly of the casing; fulcrum means arranged interiorly of the casing and carried by said supporting member and connected to said lever to provide for arcuate movement of said lever about an axis arranged approximately parallel to the plane of said one defining wall and to provide for limited lengthwise movement of said lever; link means connecting the lever and damper; an operating member fixed to one end of said lever

and extending through said opening in the supporting member and exteriorly of said one defining wall; said operating member being in the form of an arcuate-shaped sector arranged with 5 its curved surfaces arranged in arcs substantially concentric with those described by spaced points on said lever when moved about its fulcrum axis; spaced notches formed in the curved surface of said operating member which is remote from said

fulcrum, and opening away from said fulcrum; a fixed tongue arranged to engage within any selected one of said notches when the lever is at one extremity of its lengthwise movement and to clear the surfaces defining said notches when the lever is at its other extremity; and means for urging said lever lengthwise so as to effect engagement of said tongue and notches. 5
